UNITED STATES PATENT OFFICE.

EDWARD F. POOLEY, OF PHILADELPHIA, PENNSYLVANIA, ASSIGNOR TO THE POOLEY COMPANY, OF PHILADELPHIA, PENNSYLVANIA, A CORPORATION OF PENNSYLVANIA.

DESIGN FOR A RADIOCABINET.

Application filed November 3, 1928. Serial No. 28,749. Term of patent 7 years.

To all whom it may concern:

Be it known that I, EDWARD F. POOLEY, a citizen of the United States, residing at The Warwick, Seventeenth and Locust Streets, Philadelphia, in the county of Philadelphia, and State of Pennsylvania, have invented a new, original, and ornamental Design for Radiocabinets, of which the following is a specification, reference being had to the accompanying drawing, forming part thereof.

The figure is a perspective view, from the front, showing a radiocabinet embodying my design.

I claim:

The ornamental design for a radiocabinet, as shown.

In testimony of which invention, I have hereunto set my hand, at Philadelphia, on this 2nd day of November, 1928.

EDWARD F. POOLEY.
